UNITED STATES PATENT OFFICE.

JOSEPH J. LUTKIEWICZ, OF PERRYSBURG, OHIO.

BURGLAR-TRAP.

1,250,605.

Specification of Letters Patent. Patented Dec. 18, 1917.

Application filed June 9, 1917. Serial No. 173,822.

To all whom it may concern:

Be it known that I, JOSEPH J. LUTKIEWICZ, a citizen of Russia, resident of Perrysburg, county of Wood, and State of Ohio, 5 have invented certain new and useful Improvements in Burglar-Traps, of which the following is a specification.

This invention relates to improvements in means for detaining burglars or other persons when unauthorizedly within a building, and has as its principal object the provision of a theft preventing device whereby persons entering a building may be detained until released.

10 A further object is to provide means which cause shutters to automatically close before windows and doors, completely barring the exit therethrough, thereby preventing the egress of any individual contained in the building, and while this invention is particularly adapted for the use of banks, jewelers and like places where valuables are displayed and stored, it is equally applicable to any building or room whatever in which 20 it is desired to protect the contents.

These and other like objects are attained by the novel construction and combination of parts hereafter described and shown in the accompanying drawings, forming a material part of this disclosure, and in which:

Figure 1 is a vertical sectional view taken through one of the automatically operated descending platforms.

Fig. 2 is a sectional view of the same 35 taken on line 2—2 of Fig. 1.

Fig. 3 is a perspective view showing the resetting or rewinding means employed.

Fig. 4 is a vertical sectional view showing the application of a shutter plate to a 40 door or window.

Fig. 5 is a sectional view taken on line 5—5 of Fig. 4.

Fig. 6 shows an adaptation of the shutter operating means.

Fig. 7 is a perspective view of the locking device used in connection therewith.

Fig. 8 is a perspective view looking from the interior of a building and indicating the application of the shutter to a door, 50 and

Fig. 9 is a similar perspective view indicating the application of a shutter to a window.

In the drawings, is shown a structure 55 having four standards 11, the lower ends of which are rigidly set in the abutments 12,

the standards assisting in the support of the floor 14, level with which is a rectangular platform 15, normally held in a raised position by transverse bolts 16, four of which 60 are indicated.

These bolts are slidably arranged in a bracket 18, and are normally pressed outward by the coiled springs 19, arranged in recesses at the top of the bracket.

65 Flexible cords 20 engage with the inner end of the bolts 16, the same passing over pulleys 21, and being attached to a spider 22, actuated by a plunger 23, provided with an extending buttonhead 24, which upon being depressed causes the bolts to be retracted permitting the platform to descend under its own weight, together with that of the person or persons upon the same.

70 A counterweight 25 upon which the bracket hub 33 normally rests, is secured on the upper end of a bar 27, affixed in the bracket hub 33, the lower end of the bar sliding in a cylindrical bushing 28, set in the foundation 29, and furnished with a 75 coiled buffer spring 30.

Attached to the hub 33 of the bracket 18 is a flexible cable 34, running over a pulley 35, attached to the lower side of the platform 15, along the pulley 37, and another 85 guide pulley 38 attached below the floor 14 to a drum 40, mounted in the bracket 41, and provided with a pinion 42, with which is engaged a spur gear 43, mounted on a shaft 44, and driven manually by the 90 crank handle 45, so as to raise the platform into an operative position after its descent, locking dogs 46 being provided so as to prevent unwinding of the cable at undesirable times.

95 From the foregoing, it will be understood that the person operating the device must stand substantially central of the platform 15 in order to press the release plunger 24, and that he or they, together with the platform, supporting bracket spider, and counterweight, will drop instantaneously into a compartment of which the standards 11 form a portion of the walls, the depth of the compartment being such as to render it 100 impossible for the person to climb out.

Referring now particularly to Figs. 1 and 2, a number of cables 50, 51, and 52 are seen to be secured by brackets 54 to the edge of the counterweight 25, the cables being guided 110 by pulleys 55, secured below the floor in which the platform 15 is located, these cables

extending to plate shutters arranged as shown in Figs. 4, 5, 6, 8 and 9, the two latter of which indicate the arrangement of the shutters to a door and window respectively.

In the former, the cable 50, after passing over the guide pulley 56, is attached to an arm 57 at the bottom of the shutter plate 58, the same having its upper edge level with the floor 14 and closely adjacent to the door 60, so that when the counterweight descends, the cable 50 is drawn by it, raising the shutter so as to completely cover the door surface.

On the opposite side of the door is a removable plate 60, the same serving as a cover for the compartment 61, in which is attached by a bracket 62, a lever 63, pivoting on the spindle 64, and having at its lower end a roller 65, adapted to contact with the shutter plate 58 and be moved by the arm 57 when the cover is raised to its extreme height, the roller 65 ultimately engaging within a recess 66, formed in the bottom of the arm 57, thereby holding the shutter in a raised position.

A foot lever 68, is pivoted on the spindle 69, carried by the bracket 70, also attached within the chamber 61 and having a curved extending portion 71 engageable with an extending element 72 formed with the lever 63, so that by removing the cover 60 and depressing the lever 68, the roller 65 is drawn from engagement with the recess 66, allowing the shutter to drop by gravity, raising the counterweight to its initial position, a spring 73 being so attached to the extension 72 as to hold the roller operatively engaged under normal conditions, it being understood that the platform is to be raised by means of the drum 40 before the shutter plates are released.

When the lever 63 is depressed, contact is also made with electric connections, indicated by the button 75, thereby announcing the fact that the shutter has been raised.

In Fig. 9 is shown an adaptation in which a similar shutter 80 is raised by the cable 81, attached to the arm, the shutter rising through the recess formed back of the floor 14 in the partition 82, and then through the sill 83 to a point in front of the windows 85, a compensating weight 82 being freely attached by a bight of the cable, between the pulleys 87 and 88, both of which are attached below the floor in an obvious manner.

From the foregoing, it will be seen when

the trap is operated, the platform descends, and simultaneously with the descent the several shutters indicated are caused to close the openings to the room in which the platform is located, completely barring egress through the windows or doors thereof.

It will be further evident that any number of shutters may be operated with equal facility by the movement of the platform, the weight of which is sufficient to partially counterbalance the combined weight of the several shutters employed which is in excess of the counterweight, thus forming a trap which will effectually detain persons entering the room unauthorized until such time as they may be released.

Having thus described my invention, what I claim as new, and desire to secure by Letters Patent, is:—

1. In a burglar trap, the combination with a room in a building having a floor and openings in the walls, of a platform in said floor, a plurality of slideable bolts, supports therefor, means for actuating all of said bolts simultaneously whereby said platform is released, means for guiding said platform in its descent, a counterweight operatively engaged with said platform, a plurality of cables engaged with said counterweight, means for guiding said cables, a plurality of slideable shutters arranged adjacent to the walls and adapted to cover the openings therethrough, means for holding said shutters when in a raised position, and means for manually releasing said shutters.

2. In a burglar trap, the combination with a room in a building having side walls and a pit below, of a vertically movable platform over said pit, a plurality of supports therefor, bolts normally sustaining said platform in a raised position, means for retracting all of said bolts simultaneously thereby permitting said platform to descend, means for raising said platform to its initial position, a counterbalancing weight secured below said platform, a plurality of shutters operable by the descent of said platform, adapted to cover openings in said walls, means engaging therebetween whereby said shutters are raised, means for holding said shutters in a normally raised position, and means accessible through the floor whereby said shutters may be released and said counterbalance returned to its normal position.

In testimony whereof I have affixed my signature.

JOSEPH J. LUTKIEWICZ.
